UNITED STATES PATENT OFFICE

THEODORE LINDBERG, OF COLUMBUS, OHIO

SOUND-REPRODUCING APPARATUS

Application filed May 20, 1926. Serial No. 110,560.

This invention relates to improvements in sound reproducers, especially designed for use in connection with radio receiving apparatus or other sound apparatus utilizing electrical sound developing and amplifying means.

In the ordinary forms of "loud speaker" used in connection with radio apparatus, it is customary to employ but a single diaphragm or other vibratory member in the translation of the electrically created impulses into audible sound waves. Due to the physical limitations of the vibratory member, such as its sides, or the materials from which it is formed, it is considered impossible to obtain therefrom the volume, overtones or true tonal shadings which are present in the original rendition, and as a result the reproduced sound is thought to possess a flat, thin or hollow character lacking in those essentials of roundness, volume and body by which pleasing and natural qualities in sound creation are determined. Again, most of the present reproducers or amplifiers have their vibratory walls formed from a single material which may respond well and naturally to certain kindred orchestral instruments, notes or tones but do not respond with equal or similar clarity to other instrumental sounds, particularly when the latter are created by instruments having no direct relationship with the materials employed in the reproducer. For example, a reproducer involving wooden amplifying walls is more likely to reproduce faithfully the music of a violin than will an amplifier having metallic walls, although the latter may be more advantageously used in the reproduction of band music.

With these and other conditions in mind, the present invention has for a principal object thereof to provide apparatus which of and in itself is capable of reproducing faithfully and clearly practically all sounds regardless of their peculiar individual properties or beams of origination. To this end the invention consists in the provision of a sound reproducer comprising a casing in which is mounted a plurality of tautly stretched diaphragm units which, collectively

considered, are formed from different materials such as metal, wood, paper or composition materials, and are adapted when simultaneously vibrated by associated electro-responsive means to produce sounds of a natural or musical quality, wherein the full range of audible sound waves is reproducible together with a balance of proportionable reproduction of the individual instruments and sounds present and created at the original sound source.

For a further understanding of the invention, reference is to be had to the following description and the accompanying drawing, wherein:

Figure 1 is a vertical longitudinal sectional view taken through the sound reproducing apparatus comprising the present invention.

Figure 2 is a horizontal sectional view taken on line 2—2 of Figure 1.

Figure 3 is a vertical transverse sectional view taken on the line 3—3 of Figure 1.

Figure 4 is an enlarged vertical sectional view taken through one of the diaphragm units of the apparatus.

Figure 5 is a diagrammatic view of a circuit arrangement.

In the particular form of the invention herein selected for illustration and description, although the invention is not limited to the specific form thereof, my improved sound reproducer is designated in its entirety by the numeral 1. Possibly, the reproducer is formed to include a cabinet or casing 2, which is formed to comprise a horizontal bottom wall 3, a vertical back wall 4, an open front wall 5, end walls 6 and a horizontal top 7. The open front wall may be provided with a screen 8, constituting a sound outlet and also to conceal internal structure.

Mounted within the cabinet is a diaphragm base 9, having its ends only connected with the casing as at 10, in order that said base may be employed in the capacity of a sounding board. Secured to the base strip as at 9 are a plurality of vertically arranged sounding board sections 11, to the vertical edges of which are connected a plurality of fins, taut membranes or dia-

phragms 12. These diaphragms are preferably in the form of ribbons or strips, and have their upper and lower edges secured as at 13 in any substantial or stationary manner to the corresponding edges of the sections 11. As indicated in Figure 1 the diaphragms are formed from different materials, such as wood, paper, metal or a molded composition material.

10 Tension is placed on the diaphragms and the latter are maintained in a partly stretched condition, by providing the sounding board sections 11 in this instance with threaded sleeves 14, in which are received set screws 15, the latter pressing upon bars 16, arranged between the rear surfaces of the diaphragms 12 and the front surfaces of the sections 11 at the points of connection of said diaphragms with the sounding board sections. Manifestly, by tightening the screws 15 the bars 16 are forced in an outward direction so as to place the diaphragms 12 under the required degree of tension, whereby the same may respond minutely to the reciprocatory movement of a stylus 17 passing axially through aligned openings 18 provided in the base 9 and the sounding board sections 11, the outer ends of the stylus of each unit is connected with the respective diaphragm of that unit and the inner or rear end of the stylus is connected with an armature 19 situated in the magnetic field of the coils 20. These coils are arranged in circuit with a source of electric signal oscillations obtained, for example, from radio receiving apparatus or other apparatus using electrical means in the development of sound. By the switch 21 shown in Figure 5 the coils 20 may be placed either in series

20 or in parallel relation with respect to each other, and I have found that by varying the electrical potential of the coils a material and noticeable difference is obtainable in the finally reproduced sound.

45 The construction set forth provides a plurality of diaphragm units each having individual or characteristic sound creating properties which, if operated separately, would not produce a clear and accurate reproduction of a complete sound but when the combination of units is employed and the units are simultaneously operated, a full and complete reproduction is secured of great naturalness and devoid of those mechanical properties so universally present in reproduced music.

What is claimed is:

1. A sound reproducing apparatus comprising a plurality of reproducing units, 60 each of said units including a diaphragm formed from a material possessing different resonating properties than those of the other of said reproducing units.

2. A sound reproducer for radio receiving apparatus comprising a cabinet, a plu-

rality of reproducing units mounted within said cabinet, each of said units including a vibratory diaphragm, said diaphragms being formed from different materials and means for vibrating said diaphragms.

3. In sound reproducing apparatus, a cabinet, a plurality of reproducing units mounted within said cabinet, vibratory sounding boards mounted within said cabinet and upon which said reproducing units are mounted, each of said units consisting of a diaphragm, the diaphragm of said units being formed from different materials, means for maintaining the said diaphragm under tension, and means for vibrating each of said diaphragms.

In testimony whereof I affix my signature.
